UNITED STATES PATENT OFFICE.

JAMES H. DYETT, OF BROOKLYN, NEW YORK, ASSIGNOR TO UNDERWOOD TYPEWRITER COMPANY, OF NEW YORK, N. Y., A CORPORATION OF NEW JERSEY.

PLATEN FOR TYPE-WRITERS OR OTHER MACHINES.

SPECIFICATION forming part of Letters Patent No. 766,332, dated August 2, 1904.

Application filed September 29, 1903. Serial No. 175,014. (No model.)

To all whom it may concern:

Be it known that I, JAMES H. DYETT, a citizen of the United States, and a resident of the borough of Brooklyn, county of Kings, city and State of New York, have invented certain new and useful Improvements in Platens for Type-Writers or other Machines, of which the following is a specification.

My present invention relates to the platens of type-writers and like machines, and has for its object to provide a light and durable platen so constructed as to minimize the noise generally produced by the impact of the type or equivalent member with platens of the customary character.

To this end my invention consists of certain features of construction, which I will now proceed to describe as embodied in the typical platen illustrated by the accompanying drawings, it being understood that various modifications may be made without departing from the nature of my invention. In the appended claim I have defined the scope of my invention.

Figure 1 is partly a longitudinal section of the platen and partly an outside view thereof, and Fig. 2 is a cross-section taken on line 2-2 of Fig. 1.

A indicates the rubber lining, which forms the outer surface of the platen. In platens as heretofore constructed this rubber lining has generally been mounted on a continuous sleeve or cylinder made of wood, and this has proved objectionable on account of the great noise produced by the striking of the types and also on account of the fact that the wooden sleeve or core is liable to shrink and warp. To overcome these defects, I mount the rubber covering A upon an internal apertured or foraminated supporting sheet or plate B, which may be made of perforated sheet metal, as shown. The central

space inclosed by this cylindrical support is interrupted by partitions or collars C, made of wood or other suitable material. Thus any sound-waves produced within said central space will not be freely propagated from one end of the platen to the other, but will be reflected by the collars or partitions C, so as to minimize the noise. The fact that the support B is apertured also assists in decreasing the noise, as the acoustic vibrations of said support are much less pronounced than if said support were imperforate.

The manner of assembling the parts may be varied. The simplest way is to wrap the support B around the collars C, then apply the covering A, and finally tack to it the end covers, as indicated at D. The customary platen-heads E, provided with trunnions E', are also secured to the end collars C—for instance, by means of screws F.

The improved construction of the platen hereinbefore described not only deadens the noise, but further presents the advantages of considerable strength, durability, and lightness.

I claim as my invention and desire to secure by Letters Patent—

A platen for type-writers and other machines, said platen being provided with a longitudinal hollow or chamber and with a sound-breaking partition within said chamber, said partition being provided with a central aperture to afford communication between the two compartments which it separates.

In testimony whereof I have hereunto set my hand in the presence of two subscribing witnesses.

JAMES H. DYETT.
